Byrnes, Stithers & Pamela

UNITED STATES PATENT OFFICE

HAROLD H. BORTHWICK, OF LITITZ, PENNSYLVANIA, ASSIGNOR TO ARMSTRONG CORK COMPANY, OF LANCASTER, PENNSYLVANIA, A CORPORATION OF PENNSYLVANIA

FLOORING UNIT

Application filed August 27, 1928. Serial No. 302,373.

This invention relates to flooring units, such as tile, and made, for example, of linoleum mix or rubber. It is customary to lay flooring of the composition tile type using 5 composition tile of regular geometrical pattern with separate interliners therebetween so as to give the desired variegated effect to the floor, and to more closely resemble ceramic tile. Several disadvantages are attendant upon this feature. The laying is 10 very expensive since the interliners are very thin and narrow and each one must be separately glued to the adjacent tile elements and to the floor. The cost of laying these interliners will add as much as twenty percent to 15 the floor cost. In addition to this it is frequently difficult to properly match the several elements making up the floor, and the number of joints is very large, thus increasing the possibilities of water finding an imperfect joint 20 and seeping through, to the detriment of the installation.

I provide a flooring unit comprising a body portion having an integral interliner. This 25 interliner may be made of the same color as the body portion or of a contrasting color, depending on the character of the floor desired. The cost of laying is materially reduced and the number of joints is reduced 30 to a minimum. Many desirable color effects may be obtained.

In the accompanying drawings illustrating various embodiments of the invention,

Figure 1 is a top plan view of square tile 35 having full width interliners on two sides thereof,

Figure 2 is a section taken on the line II—II of Figure 1 and indicating in dotted lines the position of adjacent tile,

Figure 3 is a view corresponding to Figure 1 but showing half width interliners on all sides of the tile,

Figure 4 is a section taken on the line IV—IV of Figure 3, and

Figure 5 is a top plan view of a hexagonal tile, the position of adjacent tiles being indicated in dotted lines.

The tile shown in Figures 1 and 2 comprises a body 2 and interliner portions 3 integrally therewith. The interliner extends

around two sides only of the tile. Its top surface is concaved, as indicated at 4 in Figure 2. When such tiles are laid into a floor the adjacent tiles abut, as indicated in dotted lines in Figure 2. The effect is of a floor 55 having the surfaces of the body portions lying in a plane with depressed interliners. It will be noted that the line of juncture between adjacent tiles is at the edge of the interliner and the joint is almost invisible. If 60 desired, the body portions in different tiles may be made of varying colors and the interliners may be made of substantially the same color, thus breaking the monotony of the flooring.

The lowermost point of the concave face of the interliner is removed from the seam. This is of advantage because if any small amount of water should be left lying in the depressions it will have no opportunity to 70 seep through beneath the tile units and attack the composition flooring from below.

Figure 3 shows a modified tile, and Figure 4 shows it in conjunction with other tiles of the same character. In this form of the invention the interliner portion extends all the way around each tile and has a width corresponding to half the desired spacing between body portions in the floor. Although the line of junction is at the middle of each interliner it is obscured because the highlights appear along the edges of the depressed portions. In this case, as in the case of Figure 2, the tile units may be made of different colors. It may be desirable to make the body portions and the interliner portions of the same color in each tile, but to use tiles of varying shades, in laying a floor. When this is done the interliners appear as a neutral color or which is not dominated by a shade of any one color due to highlights on the edge of the depressed portions.

Figure 5 shows a tile of the same general character as that illustrated in Figures 1 and 2, except that it is hexagonal. The interliner 3b extends around three sides of the body portion 2b. In this form, and in the form of Figure 1, it will be noted that the interliner extends between diagonally opposite corners of the body portion.

I have illustrated certain preferred forms of the invention. It will be understood however that it is not limited to these forms, but may be otherwise embodied within the scope

5 of the following claims:

I claim:

1. As a new article of manufacture, a flooring unit made of thermo-plastic material comprising a body in the form of a tile and 10 having an integral edge portion depressed below the surface of the tile portion, the edge portion presenting a concave face simulating a depressed mortar joint.
2. As a new article of manufacture, a flooring unit made of thermo-plastic material comprising a body in the form of a tile and 15 having an integral edge portion depressed below the surface of the tile portion, the edge portion presenting a concave face simulating 20 a depressed mortar joint, the edge portion being of a contrasting color from the body portion.
3. As a new article of manufacture, a flooring unit made of a thermo-plastic material 25 and adapted to be laid up with like units so as to form a continuous floor surface, the unit comprising a body in the form of a tile and having an integral edge portion on certain 30 sides only of the body, which integral edge portions are depressed below the surface of the tile portions and simulate mortar joints, those sides of the tile portion which do not have said edge portions being arranged to 35 engage edge portions on adjacent units.
4. As a new article of manufacture, a flooring unit made of a thermo-plastic material and adapted to be laid up with like units so 40 as to form a continuous floor surface, the unit comprising a body in the form of a tile and having an integral edge portion on certain 45 sides only of the body, which integral edge portions are depressed below the surface of the tile portions and simulate mortar joints, those sides of the tile portion which do not have said edge portions being arranged to 50 engage edge portions on adjacent units, the edge portions presenting concave faces.
5. As a new article of manufacture, a flooring unit made of a thermo-plastic material 55 comprising a body in the form of a tile having a plurality of sides and integral edge portions on half of the sides, which edge portions are depressed below the surface of the tile portion and simulate mortar joints, the other edges of the body portion being arranged to directly engage edge portions on adjacent tiles.
6. As a new article of manufacture, a flooring unit made of a thermo-plastic material comprising a body in the form of a tile and 60 having an integral edge portion extending not more than half way around the perimeter of the tile, which edge portion is depressed at its center and upstanding at points remote from the tile portion, the upstanding

part being adapted to abut the next adjacent unit.

In testimony whereof I have hereunto set my hand.

HAROLD H. BORTHWICK.
